UNITED STATES PATENT OFFICE.

JOSEPH KRZYZANOWSKI AND STANISLAUS WYSOCKI, OF JUZOWKA,
RUSSIA.

ELECTRICALLY-CONTROLLED TRAP-DOOR FOR MINES OR TUNNELS.

SPECIFICATION forming part of Letters Patent No. 772,661, dated October 18, 1904.

Application filed February 25, 1904. Serial No. 195,249. (No model.)

To all whom it may concern:

Be it known that we, JOSEPH KRZYZANOWSKI and STANISLAUS WYSOCKI, both subjects of the Emperor of Russia, and residents of 5 Juzowka, in the Empire of Russia, have invented a new and useful Electrically- Controlled Trap-Door for Mines or Tunnels, of which the following is a specification.

For extinguishing mine-fires, more particularly those extending very rapidly, hitherto a well-known method was employed which consists in shutting up or separating the seat of fire by two or several dams or board walls, so as to prevent, on the one hand, the fresh 10 air from entering the seat and enlarging the fire and, on the other hand, to prevent the smoke and fire-gases from passing in all directions into the other galleries through the air-roads and the air-shafts. This method is, 15 however, most defective and objectionable, for the reason that the construction of the dams or board walls only takes place after the outbreak of the fire, and it requires a rather long time for finishing them, during 20 which time the rapidly-propagating gases of the fire may already have filled all the parts of the mine between the place of fire and the air-shafts and suffocated most if not all the miners.

Our invention relates to an electrically-controlled trap-door, of which a convenient number is disposed in the ventilation system of a mine or of a tunnel in such a manner that the mine or tunnel is thereby divided 35 into a corresponding number of sections, each controlled by two or more trap-doors. Then the moment any place is on fire the respective trap-doors can be closed from a central station or other place by electricity, whereby 40 the place on fire is shut up or separated, and thus every danger of suffocation threatening the miners is avoided. The electrically-controlled trap-door is so arranged that it is normally held in its opened position in any known 45 manner, either by weights, springs, or by its own weight. It is provided with an electric motor for closing it and with one or several electromagnets for securing it in its closed position, and these electric devices are so ar-

ranged as to consume the least quantity possible of electric current.

We will now proceed to describe our invention with reference to the accompanying drawings, in which—

Figure 1 is a cross-section through a gallery and a front view of a two-winged opened trap-door and its frame. Fig. 2 is a horizontal section through the same on the line *c d* in Fig. 1. Fig. 3 is a cross-section through a gallery and a front view of a modified 55 opened trap-door and its frame. Fig. 4 is a vertical central longitudinal section through a part of this gallery and through the same trap-door; and Fig. 5 is a cross-section, on an enlarged scale, through an electric arrangement for operating the trap-door, taken, for example, on the line *a b* in Fig. 3.

Similar characters of reference refer to similar parts throughout the several views.

The trap-door (shown at Figs. 1 and 2) is 70 provided with two wings 1 1 turning around vertical axes at the sides of the frame 2. These wings 1 1 are normally held in their opened positions by means of suitable weights 3 3 and ropes or chains led over guiding-rollers, 75 which latter are mounted in brackets of any known kind (not shown) and secured to the walls of the gallery. The frame 2 may be of brickwork or any other material, and the trap-door 1 1 may be of wood, iron, or other 80 material. The two wings 1 1 are further connected by ropes or chains 4 4 with two pulleys keyed upon the arbor of an electric motor, similar to 5 in Fig. 5, outside the casing 6, the ropes or chains 4 4 being led over suitable guiding-rollers similar to 10 and 9 in Fig. 5. Within the casing 6 two electromagnets, similar to 7 in Fig. 5, are arranged, the armatures similar to 13 in Fig. 5, of which are fastened on the two wings 1 1, and the coils of 85 the two electromagnets are connected in multiple with the electric motor. In the one wire between each electromagnet-coil and the binding-post of the electric motor two contact-springs, similar to 8 8 in Fig. 5, are inserted, 90 which normally touch each other. On each wing 1 an insulated pin, similar to 11 in Fig. 5, is secured, which carries on its end a taper-

ing piece, similar to 12 in Fig. 5, of insulating material, which can enter through an opening provided in the wall of the casing 6 and detach the two contact-springs 8 8 in Fig. 5 to break the circuit. The said wire of the electromagnet-coil is further connected by a separate wire with the circuit leading to the source of electricity on the central station. It will now be evident that when from the 10 central station the respective circuit is closed, the current will first cause the electric motor to run and to wind the ropes or chains 4 4 on its pulleys against the action of the weights 3 3, thus closing the two wings 1 1 of the trap-door until the tapering pieces 12 in Fig. 5 disconnect the electric motor from the circuit, while the two electromagnets attract their armatures, and thereby secure the two wings of the trap-door in their closed positions as long as the fire is not yet extinguished 20 and all danger both for human beings and for material is not over. Only after the delivery of the miners and when no further damage from the fire need be feared the circuit is again broken from the central station, when 25 the trap-door will be released and allowed to be opened by the weights 3 3. Preferably the edges of the door-frame 2 and those of the door-wings 1 1 are lined with strips of india-rubber, asbestos, or other material for procuring a perfect air-tight closure of the trap-door, and thus preventing air and smoke from passing over. This arrangement affords the 30 advantage that the least amount of electric current will be required for closing the trap-door, as it is the electric motor which requires more electric current than the electromagnets and the former needs but make a few revolutions for closing the trap-door, whereupon it is disengaged in the manner described and only the 35 coils of the two electromagnets remain in the circuit to energize the magnets until the fire has ceased, which may be after several days or even weeks, according to the circumstances, 40 during which time the circuit must remain closed. Thus a comparatively small quantity of electric current will be sufficient for securing the respective trap-doors in their closed positions until all dangers are over. This 45 means a saving of money.

It is immaterial of what kind or construction the trap-doors are. For example, Figs. 3 and 4 show a single trap-door 1' turning around a horizontal axis on the top of the door-frame 2' and being normally held in its horizontal opened position by a lever and weight 3'. The door 1' is connected with the pulley 14 on the arbor 15 of the electric motor 5, Fig. 5, by means of a rope or chain 4', 50 led over suitable guiding-rollers 10 9. This construction of the trap-door is specially suitable for galleries in which rail-tracks are laid. In the normal state the tracks are completely free, while in the event of a fire or danger 55 the trap-door is closed in the manner de-

scribed above and secured in the closed position by the electromagnet 7 until all danger is removed and the current is broken, when the trap-door will be automatically returned to its horizontal opened position by the weight 70 3'. Of course the trap-door 1' may be held in its opened position in any other known manner by springs or weights.

The new trap-door presents the important 75 advantage that any section of the mine (or tunnel) can be shut up in a few minutes or even seconds and with perfect safety, so that the fire can be limited very quickly owing to the stoppage of the air-supply, while the smoke and fire-gases are prevented from passing into the other sections of the mine, so that the lives of the miners therein are no longer endangered, as hitherto.

The electrically-controlled trap-door can be 80 varied in many respects without deviating 85 from the spirit of our invention.

What we claim as our invention, and desire to secure by Letters Patent, is—

1. In an electrically-controlled trap-door of the class herein described, the combination 90 with a frame secured in the walls of a gallery, of a trap-door on said frame, means for normally holding said trap-door in its opened position, an electric motor secured on said frame, means for closing said trap-door on said electric motor being actuated, an electromagnet secured on said frame, the armature of which is affixed on said trap-door, a circuit connecting said electric motor and the coil of said electromagnet with a central station, and 95 means for switching said electric motor out of and the coil of said electromagnet into the circuit as the trap-door closes.

2. In an electrically-controlled trap-door of the class herein described, the combination 100 with a frame secured in the walls of a gallery, of a two-winged trap-door on said frame, means for normally holding said two-winged trap-door in its opened position, an electric motor secured on said frame, means for closing said 105 two-winged trap-door on said electric motor being actuated, two electromagnets secured on said frame, the armatures of which are affixed on the two wings of said trap-door, a circuit connecting said electric motor and the 110 coils of said two electromagnets with a central station, and means for switching out said electric motor and switching in the coils of 115 said two electromagnets when said two-winged trap-door is closed.

3. In an electrically-controlled trap-door of the class herein described, the combination 120 with a frame secured in the walls of a gallery, of a trap-door on said frame, means for normally holding said trap-door in its opened position, an electric motor secured on said frame and having on its arbor a pulley, a rope connecting said pulley with said trap-door for closing the latter on said electric motor being 125 actuated, means for guiding said rope, an 130

- electromagnet secured on said frame, the armature of which is affixed on said trap-door, a circuit connecting said electric motor and the coil of said electromagnet in multiple with a central station, two contact-springs inserted in the circuit between said coil of said electromagnet and said electric motor and normally touching each other, a pin secured on said trap-door, and a tapering piece of insulating material secured on said pin and adapted for detaching said two contact-springs so as to disengage from the circuit said electric motor after it has wound up said rope on said pulley and thereby closed said trap-door.
- 15 4. In an electrically-controlled trap-door of the class herein described, the combination with a frame secured in the walls of a gallery, of a two-winged trap-door on said frame, means for normally holding said two-winged trap-door in its opened position, an electric motor secured on said frame and having on its arbor two pulleys, two ropes connecting said two pulleys with the two wings of said trap-door for closing the latter on said electric motor being actuated, means for guiding said ropes, two electromagnets secured on said frame, the armatures of which are affixed on the two wings of said trap-door, a circuit connecting

said electric motor and the coils of said two electromagnets in multiple with a central station, two pairs of contact-springs inserted in the two connections between the coils of said two electromagnets and said electric motor, the two contact-springs in each pair normally touching each other, two pins secured on the two wings of said trap-door, and two tapering pieces of insulating material secured on said two pins and adapted for detaching the contact-springs in each of said two pairs of contact-springs so as to disengage from the circuit said electric motor after it has wound the two ropes on said two pulleys and thereby closed said two-winged trap-door.

In testimony whereof we have signed our names to this specification in the presence of 45 two subscribing witnesses.
